United States Patent Office

Des. 232,703

Patented Sept. 10, 1974

232,703

DISPLAY CONTAINER

Ernest Konzi, Montville, N.J., assignor to Sarah
Coventry, Inc., Newark, N.Y.

Filed Nov. 1, 1971, Ser. No. 194,802

Term of patent 14 years

Int. Cl. D9—03

U.S. Cl. D9—237

FIG. 1

FIG. 2

FIG. 3

FIG. 4

FIG. 5

FIG. 6

FIG. 1 is a top plan view of a display container showing my new design;

FIG. 2 is a side elevational view;

FIG. 3 is a sectional view taken on the line 3—3 of FIG. 1;

FIG. 4 is a top plan view showing a modified form of my new design;

FIG. 5 is a top plan view showing another modified form; and

FIG. 6 is a top plan view showing still another modified form thereof.

I claim:

The ornamental design for a display container, substantially as shown and described.
